UNITED STATES PATENT OFFICE

2,673,360

EXPANDABLE SHOE TREE

Henry Bascom, St. Louis, Mo.

Application June 6, 1949, Serial No. 97,363

2 Claims. (Cl. 12—128.6)

1

My invention has relation to improvements in an expandable shoe tree, and it consists in the novel features of construction more fully set forth in the specification and pointed out in the claims.

The primary purpose of the invention is to provide a shoe tree especially adapted for holding shoes for the purpose of shining or cleaning the same.

The invention comprises a bracket and what I choose to term a shoe tree adapted to be mounted in said bracket, the tree terminating in a plurality of cooperating parts as will be more fully described hereinafter.

The principal object of the invention is to provide a shoe tree that may be expanded within the shoe so as to hold the shoe securely and in the approximate shape that it would take on the foot of a wearer. It is the further object of the invention to provide such degree of expansibility to the tree that it is readily adaptable to shoes of varying sizes, whether men's or women's shoes. These advantages, together with others inherent in the invention, will be better apparent from a detailed description thereof in connection with the accompanying drawings, in which:

Figure 1 represents a side elevation of my improved shoe tree and support therefor in engagement with a shoe (shown dotted); Figure 2 is a top plan of the invention; Figure 3 is a side elevation of the bracket and shoe tree showing both its released and operative positions (the latter dotted); Figure 4 is a vertical cross section taken on the line 4—4 of Figure 1; Figure 5 is a vertical longitudinal section taken on the line 5—5 of Figure 2; Figure 6 is a vertical cross section taken on the line 6—6 of Figure 2; Figure 7 is a horizontal section taken on line 7—7 of Figure 1 showing the tree in operative position; Figure 8 is a section similar to that shown in Figure 7 with the tree in inoperative position; Figure 9 shows the application of my tree to a type of lady's shoe which does not embody a counter; and Figure 10 is a cross-sectional detail taken on the line 10—10 of Figure 9.

Referring to the drawings (for the present Figures 1 to 8, incl.) 1 represents a bracket in which is mounted an adjustable supporting arm 2 having a toe-piece L fixed to its lower extremity. The bracket 1 is provided with a longitudinally disposed channel 3, the bottom of which is provided with serrations 4 for engagement with complementary serrations 5 formed on the up-

per surface of horizontal member 6 of the supporting arm 2. The bracket also has lateral flanges 7, 7 provided with screw holes whereby it may be secured to the underside of a chair seat S or an equivalent support. In order that the bracket 1 may be secured to a vertical supporting member, such as a wall, it is also provided with a vertical component 8 having suitable perforations 9, 9 to receive screws or bolts.

10 The side walls 10, 10 forming channel 3 have downwardly extended ears 11, 11 in which is mounted a lever 12 having a horizontal component 13. The lever 12 has its free end within a slot 14 formed in a cam member 15 which is 15 pivotally mounted at 16 between ears 11, 11. The cam 15 has a depending handle 17 from opposite sides of which project pins 18, 18 adapted to engage the rounded edge 19 of component 13. Thus, when the handle is depressed the pins 18, 18 will ride over the rounded edge 19 of the component 13 so as to lock the lever 12 in the position shown dotted (Figure 3). At the same 20 time the cam 15 will engage the underside of the horizontal member 6 of supporting arm 2. This 25 causes the supporting arm to be firmly clamped between the cam member 15 and the channel 3.

The arm 2 terminates at its lower end in a horizontal component 20 which is bifurcated so as to receive a rib 21 centrally disposed within the element 22 of the toe-piece L. Traversing the space s in the bifurcated member 20 are two pins 23 and 24 so disposed that the notched extremity 25 of the rib 21 is slideable therebetween. In addition to the element 22 the toe-piece L is 30 also provided with side members 26, 26 pivotally mounted at 27, 27 to the element 22.

35 It will be observed that the horizontal component 20 of the arm 2 is provided with oppositely disposed bosses 27¹, 27¹ provided respectively with inclined faces 28, 28 and the side members 26, 26 are provided with ribs 29, 29 terminating in inclined faces 30, 30 for cooperative action with the inclined faces 28, 28 on the member 20. It is quite obvious that as the element 22 is moved inwardly on the horizontal component 20 of the arm 2 the inclined faces 28 and 30 will be brought together and as the movement of the element 22 continues the side members 26, 26 will be spread apart. The purpose of this action is to completely fill the shoe 40 that is being fitted over the toe-piece L for the purpose of shining the same (Figures 1 and 9).

45 After the shoe has been mounted on the toe-piece L the operator depresses the lever 17 to 50 lock the arm 2 firmly to the bracket 1 and at

the same time to lock the lever 12 into the position shown dotted in Figure 3. The locking of the lever 12 securely holds the shoe on to the toe-piece L so that the operator may work on the shoe either to shine or clean the shoe as desired. It will be observed that there are a plurality of pins 31 disposed in the lever 12 so as to project slightly from the rear thereof to assist in holding the shoe in place. It will also be observed that the lever 12 has a series of indentations 32 formed on its rear surface which will assist in holding certain types of shoes (particularly feminine shoes) which have only a strap 33 at the rear instead of the customary counter.

The lever member 12 is the heel engaging piece and together with the toe-piece L constitute the shoe tree as a whole.

From the foregoing it is apparent that I have provided a shoe last that is particularly adapted for purposes of shining or otherwise reconditioning shoes which hold the shoe securely in place and at the same time completely fills the same for the purpose of facilitating the operations performed thereon.

It will be observed that I have also provided oppositely disposed handle pieces 34, 34 on the shoe tree 2 to facilitate the handling thereof and remove from the supporting member S. I have also provided oppositely disposed clips 35, 35 on the shoe tree 2 wherein the shoe laces may be lodged to keep them clear of the operations when a shoe is being worked on.

Having described my invention, I claim:

1. An expandable shoe tree including a supporting bracket, an adjustable supporting arm carried by said bracket, said arm terminating in a toe-piece, a heel-piece carried by said bracket, said toe-piece and heel-piece together comprising a shoe tree the heel-piece including a lever arm, means for locking the supporting arm to the bracket, said locking means having an element engaging the lever arm of the heel-

piece to move the same outwardly from the toe-piece.

5 2. An expandable shoe tree including a supporting bracket, an adjustable supporting arm carried by said bracket, said arm terminating in a toe-piece, a heel-piece including a lever arm carried by said bracket, said toe-piece and heel-piece together comprising a shoe tree, a locking lever carried by said bracket and effective on the supporting arm, and means on said lever engaging the lever of the heel-piece to move the same outwardly from the toe-piece.

HENRY BASCOM.
